UNITED STATES PATENT OFFICE.

WILLIAM J. BURNETT, OF MINNEAPOLIS, MINNESOTA.

DESIGN FOR A BADGE OR SIMILAR ARTICLE.

No. 39,308.

Specification for Design.

Patented May 19, 1908

Application filed March 30, 1908. Serial No. 424,290. Term of patent 7 years.

To all whom it may concern:

Be it known that I, WILLIAM J. BURNETT, a citizen of the United States, residing at Minneapolis, in the county of Hennepin and State of Minnesota, have invented a new, original, and ornamental Design for Badges or Similar Articles, of which the following is a specification, reference being had to the accompanying drawing, forming part thereof.

Figure 1 is an elevation showing the face or front side of a badge embodying my new design. Fig. 2 is an elevation showing the back or rear face of the same.

I claim:

The ornamental design for a badge or similar article, as shown.

WILLIAM J. BURNETT.

In presence of—

H. D. KILGORE,
MALIE HOEL.
